MEANS AND METHOD FOR PLEATING CLOTH IN WEB FORM

Thomas E. Davis, Rock Hill, S. C., assignor to Rock Hill Printing & Finishing Company, Rock Hill, S. C., a corporation of Delaware

Application July 22, 1952, Serial No. 300,162

12 Claims. (Cl. 223—32)

1
This invention relates to the formation of pleated cloth and more particularly to a means and method by which cloth in web form may be pleated with great facility and effectiveness.

Briefly described, cloth is pleated in web form according to the present invention by gathering a cloth web widthwise from the center and folding the gathers in the web into pleats while continuously drawing the web longitudinally by means applying heat and pressure for ironing the pleats in place. This method of the present invention and the means provided for carrying it out not only offer exceptional advantage from the standpoint of operating speed as a result of the manner in which the cloth is handled in web form, but are also particularly well adapted for ironing and setting pleats in cloth that has previously been treated with a settable resin.

These and other features of the invention are described in further detail below in connection with the accompanying drawings, in which:

Fig. 1 is a side elevation illustrating the arrangement of a pleating apparatus embodying the present invention;

Fig. 2 is a plan view corresponding generally to Fig. 1;

Fig. 3 is a partial end elevation as seen from the right in Fig. 2;

Fig. 4 is a sectional detail taken substantially on the line 4—4 in Fig. 1;

Fig. 5 is a longitudinal section taken substantially at the line 5—5 in Fig. 2;

Fig. 6 is a side elevation of one of the first series of string plates;

Fig. 7 is a plan view corresponding to Fig. 6;

Fig. 8 is a side elevation of a modified form for one of the second series of string plates;

Fig. 9 is a plan elevation corresponding to Fig. 8;

Fig. 10 is a side elevation of one of the pleating dogs;

Fig. 11 is a plan view corresponding to Fig. 10;

Fig. 12 is a left end view corresponding to Fig. 10;

Fig. 13 is a right end view corresponding to Fig. 10;

Fig. 14 is a fragmentary side elevation showing the arrangement of the supporting means provided for carrying the string plates and pleating dogs;

Fig. 15 is a sectional detail taken substantially on the line 15—15 in Fig. 14;

Fig. 16 is a sectional detail taken substantially on the line 16—16 in Fig. 14;

Fig. 17 is a fragmentary detail at substantially

the line 17—17 in Fig. 2 indicating the manner in which a cloth web is gathered widthwise by the first series of string plates;

Fig. 18 is a further fragmentary detail at substantially the line 18—18 in Fig. 2 illustrating how the gathered cloth web is guided by the second series of string plates;

Fig. 19 is a similar fragmentary detail at substantially the line 19—19 in Fig. 2 representing the folding of the gathered cloth web to form pleats;

Fig. 20 is a fragmentary side elevation showing a modified arrangement of the string plates; and

Fig. 21 is an end elevation as seen from the right in Fig. 20 with the string plates removed.

With reference now in detail to the drawing, and more particularly at first to Fig. 1, the pleating apparatus shown as an embodiment of the present invention comprises a frame structure 20 as indicated generally by the reference numeral 10 on which stand brackets 11 are arranged to position a mounting pin as at 12 for a cloth supply roll R so that the cloth may be withdrawn therefrom and trained through the apparatus as represented by the broken line at W.

From the supply roll R, the cloth web W is preferably first drawn over a bowed spreader roll 13, which is also supported on the frame structure 10 in the usual manner as shown, and then over an elevated guide roll 13' from which it is trained vertically downward through further opening means such as air-operated selvage guides as represented at 14 and under a further guide roll 14' to be taken directly into the pleating elements to be described below. The web W is thus positively maintained open and transversely taut until the pleating elements are reached.

Immediately beyond the last mentioned guide roll 14', the frame structure 10 is next arranged to carry complementary top and bottom supporting means 15 and 16 in vertically spaced relation to dispose a first series of entrance string plates 17 and a second series of exit string plates 18 for action on the cloth web W so that it is gathered transversely in preparation for the folding of continuous longitudinal pleats therein. Each of these supporting means 17 and 18 comprise a first rail element 19 formed with symmetrical leg portions as at 19' extending diagonally of the frame structure 10 from the center thereof and in the direction of travel of the web W; and a second rail element 20 extending transversely of the frame structure 10 adjacent the extending ends of the first rail leg portions 19' (see Fig. 2).

Both of these first and second rail elements 19 and 20 of the complementary top and bottom supporting means 15 and 16 are undercut on their opposed faces to a tenon form as at 21 and 22, respectively (compare Figs. 5 and 14), adapting them as a mounting base for the previously mentioned string plates 17 and 18. The form of each string plate 17 of the first series is shown in Figs. 6 and 7 as comprising flat plates having rounded entrance noses as at 17' and fitted with mounting pads 23 having dovetail grooves 24 cut therein for interfitting with the tenon form 21 of the opposed faces of the first rail elements 19. In the case of the string plates 17 these dovetail grooves 24 in the mounting pads 23 are cut angularly in correspondence with the diagonal disposition of the first rail leg portions 19', so that the string plates 17 are displaced longitudinally with respect to the frame structure 10, and to the direction of travel of the cloth web W, when mounted in place on the rail element 19.

The string plates 18 of the second series are formed in exactly the same way except that the mounting pads 25 with which they are fitted have dovetail grooves cut therein squarely to correspond with the transverse disposition of the second rail element 20. The mounting pads 23 and 25 in each case are provided in a thickness such as to result in the spacing desired for the string plates 17 and 18, and the string plates 17 and 18 are arranged on the first and second rail elements 19 and 20, respectively, with the mounting pads 23 and 25 thereof abutting so that the complementary top and bottom supporting means 15 and 16 can be vertically spaced to dispose each series of string plates 17 and 18 in horizontally spaced internested relation (compare Figs. 17 and 18), one of the central string plates 17 being fitted with a special mounting pad 23' to fit the center of its supporting rail 19 with an internesting disposition as indicated in Fig. 17. Each series of string plates 17 and 18 may be clamped or secured in place on the rail elements 19 and 20 either individually or as a group by any convenient means (not shown).

The vertical spacing of the top and bottom supporting means 15 and 16 is made adjustable through supporting studs 26 and 27 that are fitted with opposed pair of adjusting nuts as at 28 and 29, and 30 and 31, respectively, to engage cross supporting rails 32 and 33 at the front end of the respective supporting means 15 and 16, and swivel lugs 34 and 35 that are carried in side framing plates 36 and 37 at the rear thereof. By suitable manipulation of the adjusting nuts on these supporting studs 26 and 27, the vertical spacing of the top and bottom supporting means 15 and 16 may not only be set as desired, but the front and rear ends of these supporting means 15 and 16 may also be independently adjusted to tilt the supporting means 15 and 16 with respect to each other (by virtue of the swivel arrangement of the lugs 34 and 35) and thereby readily vary or adjust the gathering action between the string plates 17 and 18 in proper relation to the subsequent pleat folding action as will be explained in further detail presently.

The above noted supporting studs 26 and 27 are in turn supported on a carriage frame 38 (compare Figs. 14 and 15) that is fitted with cross shafts 39 having roller sleeves as at 40 thereon (see Fig. 4) by which the carriage frame 38 is adapted for shifting longitudinally on the frame structure 10. During normal operation,

the carriage frame 38 is held in a fixed position against a stop plate 41 at the rear of the frame structure 10 by the pull of the web W as it is drawn through the pleating elements, but at other times may be shifted forwardly on the frame structure 10 to facilitate initial threading of the web W and the like. Control of this shifting movement is effected through racks 42 attached at the bottom face of the carriage frame 38 along each side thereof to engage pinions as at 43 carried on an actuating shaft 44 mounted on the frame structure 10 and extending therefrom to carry also a manipulating handwheel 45. This shiftable arrangement of the carriage frame 38 is particularly advantageous in that it allows the pleating elements to be shifted for easy access away from the final draw roll pair (to be described presently) while otherwise allowing this roll pair to be disposed for acting on the cloth web W immediately as it leaves the pleating elements. It should also be noted that as the previously mentioned elevated guide roll 13', selvage guide means 14, and further guide roll 14', are disposed immediately ahead of the string plate supporting means 15 and 16, they should also be made shiftable with the pleating elements by arranging them on suitable framing extending as at 38' from the carriage frame 38.

The actual folding of pleats in the cloth web 30 W is done by a series of pleating dogs 46 that are disposed to follow the second series of string plates 18 and fold the gathers formed by the string plates 17 and 18 into pleats. These pleating dogs 46 are also supported on the shiftable carriage frame 38 by means of further supporting studs 47 that have opposed pairs of adjusting nuts 48 and 49 thereon to engage end lugs as at 50 and 51 which are fitted to top and bottom supporting rails 52 and 53 extending transversely of the frame structure 10 for carrying the series of pleating dogs 46. The opposed faces of these supporting rails 52 and 53 are also undercut to a tenon form as at 54 and 55, respectively, and the pleating dogs 46 are also fitted with mounting pads 56 having dovetail grooves cut therein as at 57 for mounting on the supporting rails 52 and 53 in the same manner as already described for the string plates 17 and 18, the mounting pads 23, 25 and 56 all having the same thickness so that a corresponding transverse spacing is provided for both series of string plates 17 and 18 and the pleating dogs 46 as well.

The form of the pleating dogs 46 is shown in detail in Figs. 10 to 13 of the drawings in which it will be seen that each pleating dog 46 is formed with a folding lip 58 at the edge thereof opposite from the edge at which it is fitted with the mounting pad 56. This folding edge 58 is shown in Fig. 10 in relation to a broken line representation at W' of the medial cloth line as a web being pleated is drawn through the pleating dogs 46. At the entrance end of the dogs 46 (to the left in Fig. 10), the folding lip 58 is disposed beyond the medial cloth line W' and is of relatively narrow lateral extent so that it is adapted to receive a gather in the cloth web W from the string plates 18 while exerting only a slight folding action in cooperation with the folding lip 58 of an adjacent internested pleating dog 46 (compare Figs. 5 and 19). Proceeding toward the exit end of the pleating dogs 46 (to the right in Fig. 10), however, the folding lip 58 is arranged so that it slopes toward the medial cloth line W' and increases in lateral extent to lay a gather 75 in the cloth web W over into a pleat (again in

cooperation with the folding lip 58 of an adjacent internested pleating dog 46).

The manner in which the gathering of the cloth web W by the string plates 17 and 18, and the folding of these gathers into pleats by the pleating dogs 46, occurs is illustrated in Figs. 17, 18 and 19 of the drawings. Fig. 17 represents a transverse sectional detail through the first series of string plates 17 at substantially the line 17-17 in Fig. 2, the most forwardly disposed central string plates 17 being shown in full lines, and several of the string plates 17 to each side being shown in section as an indication of their progressively displaced positions longitudinally of the frame structure 10 by virtue of the previously described diagonal disposition of the first rail leg portions 19'. As a result of this progressively displaced arrangement, the cloth web W is acted upon first by the foremost centrally disposed string plates 17 to gather the web W widthwise from its longitudinal center first. Then, successively, the string plates 17 at each side come into play, as the web W is drawn through them, to form additional gathers in order outwardly from the central gather first formed until the web W has passed through all of the string plates 17 and has gathers formed completely across its width by the string plates 17.

The action of the second series of string plates 18 is represented in Fig. 18. These string plates 18 are arranged in transverse alignment as previously noted and serve to receive the gathered cloth web W from the first series of string plates 17 and direct the entrance of this gathered web into the pleating dogs 46. For some cloths, this action of the second series of string plates 18 can be obtained satisfactorily by spacing them to follow the first series of string plates 17 without any interconnection. For cases where the cloth is more difficult to handle, however, a modified arrangement is illustrated in Figs. 8, 9, 20 and 21 of the drawings that provides for continuous guiding of the gathered cloth web W between the first and second series of string plates.

In this modified arrangement a somewhat different form of string plate is used as illustrated best at 59 in Figs. 8 and 9 which shows a modified second series string plate for comparison with the first series string plate 17 shown in Figs. 6 and 7. This modified second series string plate 59 is formed of a flat plate fitted with a mounting pad 60 having a square cut dovetail groove 61 therein in all respects like that of the string plates 18, except that the rounded string plate nose 59' is arranged rearwardly in this case at the exit 55 (rather than the entrance) end of the string plate 59, and the active edge of the string plate 59 as well as the edge of the rounded nose 59' is grooved as shown at 62 in Figs. 8 and 9. Similarly edge grooved first series string plates 63 are also employed in this modified arrangement, although the modified first series string plate 63 are otherwise arranged and disposed just as the previously described string plates 17 were (compare Figs. 5 and 20).

The purpose of employing the edge grooved string plates 59 and 63 is to provide for connecting them in succeeding pairs with strand elements as shown at 64 in Fig. 20, formed of any suitable material such as piano wire, that may be located by the edge grooved string plates 59 and 63 and tensioned between them as a continuous guiding means while introducing a minimum additional drag on the cloth. Alternatively, the succeeding pairs of string plates might each be formed as 75

a unit, rather than separately in first and second series, and thereby provide a continuous active edge for the string plates, but such an arrangement would impose substantially greater drag on the cloth web W being pleated than the strand element arrangement described above.

A suitable means for securing the strand elements 64 in this manner may consist of a pair of cross rails 65 and 66 mounted between the previously noted side framing plates 37 (or 36) just ahead of the second series of modified string plates 59, with the extending edge of one cross rail of this pair such as 65 having anchoring slots 67 formed therein for fixing one end of the strand elements 64, and with the extending face of the other cross rail of this pair such as 66 being fitted with adjustable screw eyes 68 at which the strand elements 64 may be tightened to the proper tension.

Fig. 19 illustrates the action of the pleating dogs 46 on the string plate gathered cloth web W. The cooperating folding lips 58 of these dogs 46 act to lay the cloth gathers over into pleats so that the web W is returned again to more or less 25 a common widthwise plane as it leaves the dogs 46 but is now formed with longitudinally continuous pleats across its width.

The means by which the cloth web W is drawn through the pleating operation according to the present invention comprises a draw roll pair as shown at 69 and 70 in Fig. 1 that serves as well for ironing into the web W the pleats that have been formed. This draw roll pair 69 and 70 may be arranged in a separate stand (not shown) or be carried on the frame structure 10 as desired. Preferably, the bottom roll 70 of the pair is provided in a larger diameter to serve as a backing roll, while the top roll 69 is fitted with axial ports as at 71 allowing circulation of a heating medium such as steam therethrough for applying heat as well as pressure at the nip of rolls 69 and 70. Such an arrangement adapts the apparatus particularly well for handling cloth webs W that have been treated with a settable resin, such as urea-formaldehyde, to obtain a permanent finish and which may also be utilized according to the present invention to set the pleats formed in the cloth web W.

The present invention has been described in detail above for purposes of illustration only and is not intended to be limited by this description or otherwise except as defined in the appended claims.

I claim:

1. Apparatus for pleating cloth in web form comprising a frame structure, a first transverse series of flat, vertically disposed, entrance string plates carried on said frame and arranged in spaced internested relation and progressively displaced longitudinally from the longitudinal center of said series toward each end for gathering said cloth widthwise from the longitudinal center of a web thereof trained through said string plates, a second transverse series of flat, vertically disposed, exit string plates carried on said frame structure and arranged in corresponding spaced internested relation but transversely aligned for disposing the gathered cloth web to be pleated, and a succeeding transverse series of pleating dogs arranged on said frame structure for folding pleats in the gathered cloth longitudinally of said web.

2. Apparatus for pleating cloth in web form comprising a frame structure, a first transverse series of flat, vertically disposed entrance string

plates carried on said frame structure and alternately extending upwardly and downwardly in spaced internested relation and arranged with pairs of said upwardly and downwardly extending string plates displaced progressively in a longitudinal direction from the center of said series toward each end, whereby a cloth web drawn through said first series of string plates will be gathered widthwise from the longitudinal center of said web, a second transverse series of flat, vertically disposed, exit string plates carried on said frame structure and arranged beyond said first series and likewise alternately extending upwardly and downwardly in corresponding spaced internested relation but arranged in common transverse alignment for maintaining the gather in a cloth web drawn therethrough from said second series of string plates.

3. Apparatus for pleating cloth in web form as defined in claim 1 and further characterized in that a pair of draw rolls is arranged beyond said pleating dogs for drawing said cloth web through said first and second series of string plates and said pleating dogs for gathering and pleating.

4. Apparatus for pleating cloth in web form as defined in claim 3 and further characterized in that at least one of said draw rolls is heated for ironing and setting the pleats in said cloth web.

5. Apparatus for pleating cloth in web form as defined in claim 2 and further characterized in that selvage guide means are arranged just ahead of said first series of string plates and a web guide roll is disposed between said guide means and first string plates to have the cloth web angled thereover before entering said first string plates for maintaining said web open and transversely taut until said first string plates are reached.

6. Apparatus for pleating cloth in web form as defined in claim 2 and further characterized in that the extending edges and the opposite ends of said first and second series of string plates are grooved, and strand elements are disposed in said grooves and extended under tension between the corresponding string plates of said first and second series for continuous guiding of said gathered cloth web between the string plates of said first and second series.

7. Apparatus for pleating cloth in web form comprising a frame structure, a first transverse series of flat, vertically disposed, entrance string plates carried on said frame structure and alternately extending upwardly and downwardly in spaced internested relation and arranged with pairs of said upwardly and downwardly extending string plates displaced progressively in a longitudinal direction from the center of said series toward each end, whereby a cloth web drawn through said first series of string plates will be gathered widthwise from the longitudinal center of said web, a second transverse series of flat, vertically disposed, exit string plates carried on said frame structure and arranged beyond said first series and likewise alternately extending upwardly and downwardly in corresponding spaced internested relation but arranged in common transverse alignment, and a succeeding transverse series of pleating dogs having cooperating folding lips mounted alternately in internested relation on said frame structure with a transverse spacing corresponding to the string plates of said first and second series for folding pleats in the gathered cloth longitudinally of said web, the extent of internesting of said first and second series of string plates being independently adjustable for

regulating the extent of gathering of said cloth web in relation to the gather necessary for folding into pleats by said pleating dogs.

8. Apparatus for pleating cloth in web form comprising a frame structure, a top supporting means and a complementary bottom supporting means carried on said frame structure in vertically spaced relation, each of said top and bottom supporting means having a first rail element formed with symmetrical leg portions extending diagonally of said frame structure from the center thereof and a second rail element extending transversely of said frame structure adjacent the extending ends of said diagonal leg portions, a first series of string plates mounted alternately on the diagonal leg portions of said first rail elements in spaced internested relation, a second series of string plates mounted alternately on said second rail elements in internested relation with a transverse spacing corresponding to the string plates of said first series, a further pair of top and bottom supporting rail elements carried transversely on said frame structure in vertically spaced relation adjacent the second rail elements of said first mentioned top and bottom supporting means, a series of pleating dogs having cooperating folding lips mounted alternately in internested relation on said last mentioned rail elements with a transverse spacing corresponding to the string plates of said first and second series.

9. Apparatus for pleating cloth in web form as defined in claim 8 and further characterized in that said top and bottom supporting means and said further pair of supporting rail elements are carried on said frame structure for shifting longitudinally thereof to facilitate initial threading of a cloth web through said string plates and pleating dogs, and the vertical spacing at each longitudinal end of said top and bottom supporting means and said further pair of rail elements is independently adjustable.

10. The process of pleating cloth in web form which comprises first maintaining widthwise tension on a cloth web in advance of a web guide surface, angling said web over said guide surface, then gathering said web widthwise from the center beyond said guide surface while drawing said web longitudinally, and then folding the gathered portions of said longitudinally drawn web to form longitudinal pleats therein.

11. The process of pleating cloth in web form which comprises forming uniform gathers in a cloth web widthwise thereof from the center and folding the gathers in said web into pleats while drawing said web longitudinally by means applying heat and pressure thereto for ironing the pleats formed therein.

12. The process of pleating cloth in web form which comprises impregnating a cloth web with a settable resin, and then forming gathers in said cloth web widthwise thereof from the center and folding said gathers to form pleats while drawing said web longitudinally by means applying heat and pressure thereto for ironing and setting said pleats therein.
